COMBINED CASKET HANDLES AND BRACKETS

Charles F. Winburn, Cincinnati, Ohio, and Herbert K. Y. Sun, Sunman, Ind., assignors to Batesville Casket Company, Inc., Batesville, Ind.

Filed Apr. 24, 1972, Ser. No. 247,240

Term of patent 14 years

Int. Cl. D8—06

U.S. Cl. D31—11

FIG. 1 is a perspective view of combined casket handles and brackets showing our new design;

FIG. 2 is a front elevational view;

FIG. 3 is a side elevational view;

FIG. 4 is a bottom plan view on a reduced scale.

We claim:

The ornamental design of combined casket handles and brackets, substantially as shown.
